UNITED STATES PATENT OFFICE.

WILLIAM E. PARNALL, OF CALUMET, AND CHARLES H. KRAUSE, OF SOUTH LAKE LINDEN, MICHIGAN.

STAMP-MILL.

SPECIFICATION forming part of Letters Patent No. 689,219, dated December 17, 1901.

Application filed September 3, 1898. Serial No. 690,154. (No model.)

To all whom it may concern.

Be it known that we, WILLIAM E. PARNALL, residing at Calumet, and CHARLES H. KRAUSE, residing at South Lake Linden, in the county 5 of Houghton and State of Michigan, citizens of the United States, have invented certain new and useful Improvements in Stamp-Mills, of which the following is a specification, reference being had to the accompanying drawings, forming a part thereof.

Our invention relates particularly to stamp-mills for crushing copper ore such as is obtained in the Lake Superior region, in which flakes or pieces of pure metal varying in size 15 are found embedded in or adhering to very hard rock.

Its main objects are to increase the capacity and generally to improve the construction and operation of machines of this class.

20 It consists in certain novel features of construction and arrangements of parts, as hereinafter particularly described, and pointed out in the claims.

In the accompanying drawings like letters 25 designate the same parts in both figures.

Figure 1 is a vertical medial section on the line 2 2, Fig. 2, of a stamp-mill embodying our invention; and Fig. 2 is a horizontal section of the same on the line 1 1, Fig. 1.

30 For crushing ore of the kind above mentioned powerful steam-actuated stamp-mills are generally employed. These mills are usually provided with single stamps and housings or casings inclosing the space around 35 the stamps and above the mortars and constituting permanent framework for carrying the roof over the mortars and for holding the screens. The housing or casing has from one to four openings—ordinarily two or four, ar-

40 ranged on opposite sides of the stamp and mortar—and these openings are provided with straight flat or plane screens, which are usually inclined outward toward the top and are located at some distance from the stamp

45 and the cavity in the mortar. It will be apparent that only a small part of such plane screens can be perpendicular to the splash, which radiates from all sides of the stamp, and that pieces of free metal small enough

50 to pass straight through holes in that part of a screen which is perpendicular to the splash

cannot pass obliquely through holes of the same size in other parts of the screen, but will be thrown back into the mortar and subjected again to the powerful blows of the 55 stamp. This repeated action of the stamp upon free pieces of copper is undesirable for several reasons: It reduces the capacity of the mill and correspondingly increases the cost of crushing a given quantity of ore, it 60 increases the losses in fine material and slimes which are produced by the repeated pounding of the free metal, and it impairs the quality and value of the copper, particularly for electrical purposes, because the 65 longer the copper is retained in the mortar the greater will be the percentage of iron mixed with it from the constant wear and abrasion of the stamp, stave-liners, and parts of the mill which are exposed to the cutting 70 and abrading action of the hard crushed rock, sand, or pulp. The permanent frame work forming a considerable part of the inclosure around the stamp and mortar reduces to that extent the screening area, and consequently 75 the discharging capacity, of such mills and must be protected by linings which are exposed to the powerful splash of sharp pulp or sand from the heavy stamp, and consequently are subjected to rapid abrasion and wear and must 80 be frequently renewed, thus entailing constant care, trouble, and expense. For crushing ore of the character hereinbefore mentioned mills having more than one stamp working in the same inclosure are impracticable 85 on account of the strong splash of hard sharp pulp or rock, which would rapidly cut away the stamp-shoes and lower parts of the stamps. Furthermore, the splash of each stamp intercepts that of the other stamp or stamps in 90 the same inclosure and prevents to a considerable degree the discharge through the screens of the crushed ore carried by the splash. It follows, therefore, that in the powerful stamp-mills above referred to having plane screens 95 arranged in the openings of a permanent casing or framework which forms a considerable part of the inclosure around the mortar, particularly in mills having more than one stamp in the same inclosure, their capacity to crush 100 the ore and free the metal is much greater than their capacity to discharge or get rid of

the freed metal. The total output of these mills is thus materially reduced, loss in fine material or slimes is largely increased, and the quality and value of the metal are impaired. By our improved construction and arrangement of parts the screens are more advantageously and effectively disposed, and their effective area for the discharge of the pulp or sand and free metal is increased to a maximum, while the area of permanent parts of the mill exposed to the abrading and destructive effect of the splash is reduced to a minimum, the capacity of the mill is greatly increased, loss in fine material and slimes is reduced, the quality of the metal obtained is improved, and the time, trouble, and expense required to renew linings and parts exposed to abrasion are to a great extent avoided. By making the screen and splash-pan in separately-removable sections a great saving is effected, since those parts that are subjected to more rapid wear may be renewed from time to time as they become worn out and unfit for use without discarding or disturbing other parts which may still be serviceable. The mortar and stamp being completely surrounded by the screen and splash-pan, which can be easily removed in sections, either partially or wholly, are more easily accessible for inspection and repair than when they are partially inclosed on the sides by a permanent casing or housing.

Referring to the drawings, illustrating a stamp-mill embodying our invention in its preferred form as to the construction and arrangement of the essential parts of the machine, A designates the mortar, which is formed in the upper side with a central cavity for holding the ore to be pulverized or crushed, and with a channel *a* around said cavity for catching and conducting off the pulp or sand. It is also formed outside of said channel with flanges or projections *a' a'* for the support and attachment of columns B, which carry at their upper ends the roof C. These columns are cored out to receive the rods or bolts D, which pass through them, the flanges or projections *a'* on the mortar, and the roof C and are provided at their ends with nuts for firmly binding and holding the several parts together.

E is the stamp, which has a vertical reciprocating movement and a slow rotary movement imparted thereto by the usual or any suitable means, which it is not deemed necessary to illustrate or particularly describe, as they do not constitute a part of the invention claimed and are not essential to a clear understanding thereof. The stamp is provided in the usual way with a detachable chilled or hardened iron shoe *e*. The central cavity in the mortar is provided on the sides with the usual stave-liners F and at the bottom with a die G, which is held in place by a ring H. The roof C is formed with an opening *c*, through which the stamp-shaft projects and through which the ore to be crushed

is fed, with water, into the mortar. These stave-liners, die, and ring are, like the stamp-shoe, usually made of chilled iron and are readily removable, so that they can be easily replaced when worn out. The channel *a*, the under side of the roof, and those parts of the machine which are exposed to the splash and with which the pulp or sand comes in contact are protected by linings of chilled iron, boiler-plate, or other suitable material which can be easily removed and renewed from time to time.

The mortar A is supported by an anvil I and is held in place thereon by a raised portion of the top of the anvil fitting a recess in the bottom of the mortar, as shown in Fig. 1, and it is prevented from turning by lugs *a²*, cast on the mortar and engaging with projections on the anvil, as shown in Fig. 2. A screen or grate composed of sections J J completely surrounds the central cavity in the mortar within the channel *a*. The screen-sections are preferably made of perforated metal plates, which are clamped between and strengthened at their edges by frames *j j*. These frames bear at the top and bottom against and are supported on the inside by shoulders formed or provided for the purpose on the upper side of the mortar and on the under side of the roof. The screen is preferably made of approximately cylindrical form and its sections arranged concentrically with the vertical axis of the stamp and mortar; but any form of arrangement whereby the several parts of the screen will be disposed approximately perpendicular or transverse to the direction of the splash from the stamp and mortar are within the spirit and intended scope of the invention. A splash-pan composed of sections K K of sheet or plate metal corresponding in number, form, and arrangement with the sections of the screen surrounds the screen and serves to intercept the pulp or sand discharged through the screen and to deflect the same downward into the channel *a*, from which it is conducted through one or more spouts *a³ a³* (shown in Fig. 2) into launders. The splash-pan sections are bent inward at the sides which are adapted to rest against the sides of the screen-frames, and they are cut away or left open at the bottom, as shown in Fig. 1, to allow the pulp or sand to flow underneath them into the channel *a*. Each splash-pan section K and the adjacent screen-section J are held in place by screw rods or bolts L, which are threaded in the columns B, extend radially inward therefrom, and bear at their inner ends against the inturned sides of the splash-pan sections. These rods or bolts L are provided with jam-nuts *l*, by which they are locked in place when they are set up against the splash-pan sections K. With this construction and arrangement of the screen and splash-pan and the means shown and described for holding the sections in place any section can be readily removed and re-

placed without disturbing the others, and the columns and main parts of the framework of the machine are protected by the splash-pan against contact with the pulp or sand, which 5 rapidly wears away parts of the machine exposed to it. The capacity of the machine is also materially increased. The maximum amount of ore that it has been possible to crush with a stamp-mill of this class as here- 10 tofore constructed is about four hundred tons in twenty-four hours; but with a machine substantially like that herein shown and described nearly or quite six hundred tons can be crushed in the same time.

15 We do not wish to be understood as limiting ourselves to the exact details of construction as shown and described except as to those claims in which such details are expressly included.

20 We claim—

1. In a stamp-mill the combination with a single stamp provided with a detachable hardened shoe and a mortar having a cavity provided with a removable hardened die and hardened stave-liners constructed and arranged to receive the impact of the pulp and to direct the same upwardly and outwardly on all sides, of a removable cylindrical screen surrounding the stamp concentrically there- 25 30 with so as to be approximately perpendicular to the direction of the splash passing through it on all sides of the mortar, and a removable splash-pan surrounding said screen and open at the bottom so as to intercept the pulp passing through said screen and to afford a free and constant discharge therefor, substantially as and for the purposes set forth.

2. In a stamp-mill the combination with a single stamp provided with a detachable hardened shoe and a mortar formed with a central cavity and with a channel surrounding said cavity which is provided with a removable die and stave-liners constructed and arranged to receive the impact of the pulp and to direct the same upwardly and outwardly on all sides, of a removable cylindrical screen arranged concentrically with said stamp between the cavity and channel in the mortar, and a removable imperforate splash-pan in- 45 50 closing a space outside of said screen and open at the bottom so as to afford a free discharge for the pulp into the channel in the mortar, substantially as and for the purposes set forth.

55 3. In a stamp-mill the combination with a single stamp provided with a detachable hardened shoe and a mortar having a cavity provided with a removable hardened die and stave-liners constructed and arranged to re- 60 ceive the impact of the pulp and to direct the same upwardly and outwardly on all sides, of a cylindrical screen surrounding the stamp concentrically and composed of separately-re- 65 70 movable sections, and a splash-pan surround-

ing said screen and composed of correspond- 65 ing separately-removable sections opening at the bottom into a suitable discharge-conduit, substantially as and for the purposes set forth.

4. A stamp-mill comprising the framework, a stamp, a mortar and its cavity, a screen 70 composed of sections surrounding the stamp and the cavity of the mortar, and a splash-pan composed of corresponding sections surrounding the screen, both the screen and the splash-pan being interposed between the 75 stamp and the framework and protecting the framework against the splash from the stamp, substantially as described.

5. A stamp-mill comprising a stamp, a mor- 80 tar having a cavity and a channel surround- 85 ing the cavity, columns arranged outside of said channel, a roof supported above the mortar upon said columns, bolts passing through said columns and roof and provided with nuts firmly binding and securing the parts to- 90 95 gether, a screen surrounding the cavity in the mortar inside of said channel, and a removable splash-pan interposed between said screen and said columns, substantially as and for the purposes set forth.

6. A stamp-mill comprising a stamp, a mor- 95 tar and its cavity, columns rising from the outer portion of the mortar, a roof supported on the columns, said mortar and roof being pro- 100 105 vided with corresponding shoulders, a screen composed of sections surrounding the cavity in the mortar inside of said columns and bearing on the inside at the top and bottom against the shoulders of the roof and mortar, and radially-disposed screw rods or bolts threaded in said columns and holding said screen-sections from the outside against said shoulders, substantially as and for the purposes set forth.

7. A stamp-mill comprising a stamp, a mor- 105 tar having a cavity and a channel around the 110 cavity, columns rising from the mortar out- 115 side of said channel, a roof supported on said columns, said roof and mortar having corre- 120 sponding shoulders or abutments, a screen composed of sections surrounding the cavity in the mortar, a splash-pan composed of cor- 125 responding sections having inwardly-turned sides adapted to rest against the sides of the screen-sections, and screw rods or bolts threaded in said columns transversely thereto and adapted to bear at their inner ends against the inturned sides of the splash-pan sections and to hold them with the screen-sections against the shoulders or abutments on the mortar and roof, substantially as and for the 130 purposes described.

In witness whereof we hereto affix our signatures in presence of two witnesses.
